ABSTRACT OF THE DISCLOSURE

An electric furnace in which resistive heating elements have a non-uniform or non-linear resistance to compensate for gradual and exponential thermal and radiant heating losses, which are greater at the extremities of the furnace and which gradually decrease as the central portion of the furnace is approached.

The present invention relates in general to electric furnaces, and more particularly to an electric furnace employing resistive elements for converting electric power into thermal energy.

Conventional tubular electric furnaces of the diffusion type or the type employed in the manufacture of semiconductor or photoconductor devices generally comprise three sections, namely: an entrance zone, center zone and an exit zone. It has been found that the electric furnaces of the type referred to have characteristic thermal and radiation losses. In the entrance zone, the greatest thermal and radiation losses appear at the end of the furnace. The minimum thermal and radiation losses appear at the center of the furnace. Thus, as the entrance zone progresses toward the center zone, there is a gradual decrease in radiation and thermal losses. Similarly, the exit zone has its greatest thermal and radiation losses at the end of the furnace. The minimum thermal and radiation losses appear at the center of the furnace. Hence, as the exit zone progresses toward the center zone, there is a gradual decrease in radiation and thermal losses. The thermal and radiation losses throughout the center zone is at a minimum and substantially constant. The thermal and radiation losses in the entrance and exit zones are exponential in characteristics along the axis of the tubular furnace as the measurements are taken from each end of the furnace and then progressing centrally therefrom.

An object of the present invention is to provide an electric furnace in which the heating elements thereof are constructed to compensate for the gradual characteristic thermal and radiant losses of the furnace.

Another object of the present invention is to provide an electric furnace in which the resistive heating elements are formed with a gradually varying resistance to compensate for the gradual characteristic thermal and radiant losses of the furnace.

Another object of the present invention is to provide an electric furnace in which resistive heating elements are constructed in a non-uniform or non-linear arrangement to compensate for the gradual characteristic thermal and radiant losses of the furnace.

Another object of the present invention is to provide an electric furnace in which resistive heating elements are constructed in a non-uniform or non-linear arrangement to compensate for gradual and exponential thermal and radiant losses in the electric furnace which are greater at the extremities of the furnace and gradually decrease as the central portion of the furnace is approached.

Other and further objects and advantages of the present invention will be apparent to one skilled in the art

2

from the following description taken in conjunction with the accompanying drawings, in which:

FIG. 1 is a perspective view of a tubular heating assembly for an electric furnace embodying the present invention.

FIG. 1 is an end elevation view of the tubular heating assembly shown in FIG. 1 with diagrammatical illustrated electrical circuits.

FIG. 3 is a diagrammatic illustration of the heat source elements of the present invention employed in connection with the tubular heating assembly shown in FIGS. 1 and 2.

Illustrated in FIGS. 1 and 2 is a tubular heating assembly 10 embodying the present invention, which heating assembly 10 will be encased in a conventional manner to form an electric furnace. The tubular heating assembly 10 comprises a tubular electrical insulating ceramic housing 11. Disposed within the housing 11 concentrically therewith and spaced radially inward therefrom are suitable electrical insulating ceramic inner sections 13.

The tubular heating assembly 10 may be divided into three zones, namely: entrance zone A, central zone B and exit zone C. Supported by the inner wall of the inner ceramic sections 13 are uniformly wound primary or inner heating elements 21-23. The primary heating elements are disposed within the entrance zone A, center zone B and exit zone C, respectively. Each primary or inner heating element is made of suitable resistance material uniformly wound in spiral or helical configurations along the inner wall of the inner sections 13 and the uniformly wound windings thereof are suitably spaced apart and have uniform resistance throughout the turns thereof. The axis of the heating elements 21-23 are coincident with the axis of the housing 11. The turns are conveniently separated and insulated by well-known ceramic T-form separators. It is within the contemplation of the present invention that the primary heating elements be a continuous and single winding.

A suitable source of electric power, such as a control system 25, supplies electric power to the primary heating elements 21-23 for producing furnace heat. Toward this end, transformers 26-28 (FIG. 3) have the primary windings thereof connected to the source of power 25 and have the secondary windings thereof connected to the primary heating elements 21-23, respectively. Should a more simplified control system be desired, the heating elements may be connected directly to a source of electrical energy.

It has been found that the tubular heating assemblies of the type referred to have characteristic thermal and radiation losses. In the entrance zone A, the greatest thermal and radiation loss appears at the end of the tubular housing 11 adjacent to the entrance opening 12. The minimum thermal and radiation loss for the entrance zone A appears at the end thereof adjacent to the center zone B or more accurately intermediate the ends of the center zone B. As the entrance zone A progresses from the end of the housing 11 adjacent to the entrance opening 12 toward the center zone B taken in the axial direction of the housing 11, there is a gradual decrease of thermal and radiation losses for the assembly 10, which thermal and radiation losses for the path described, when projected in the form of a graph, appear as an exponential curve.

In a like manner, the exit zone C has its greatest thermal and radiation loss at the end of the tubular housing 11 adjacent to the rear opening in the housing 11. The minimum thermal and radiation loss for the zone C appears at the end thereof adjacent to the center zone B or more accurately intermediate the ends of the center zone B. As the exit zone C progresses from the end of the housing 11 adjacent to the exit opening in the housing 11, toward the center zone B taken in the axial direction

of the tubular housing 11, there is a gradual decrease of thermal and radiation losses for the tubular heating assembly 10, which thermal and radiation losses for the path described, when projected in the form of a graph, appear as an exponential curve.

Across the center zone B of the tubular heating assembly 10, the thermal and radiation losses are relatively uniform and constant. It is the center zone B that has the maximum temperature control and minimum thermal and radiation losses.

According to the present invention, secondary outer heating elements 30 and 31 (FIG. 3) are mounted in the entrance zone A and the exit zone C, respectively, between the outer ceramic tubular insulating housing 11 and the inner ceramic insulating sections 13 to compensate for the above-mentioned thermal and radiation losses and extend partially within the center zone B. Since the radiation and thermal losses in the entrance zone A and the exit zone C, respectively, are graphically represented in the form of an exponential curve, the secondary outer heating elements 30 and 31 are non-uniform and non-linear, respectively, to produce uniform heating in the axial direction throughout the entrance zone A and the exit zone C, respectively.

Each secondary or outer heating element is made of suitable resistance material wound in spiral or helical configurations between the inner wall of the tubular housing 11 and the outer wall of the ceramic sections 13 and the turns of the windings thereof are suitably spaced apart. The axis of the heating elements 30 and 31 are coincident with the axis of the housing 11. The turns are conveniently separated and insulated by well-known ceramic T-form separators. Thus, the primary heating elements 21-23 are electrically insulated from the secondary heating elements 30 and 31.

A suitable source of electric power, such as a control system 40, supplies electric power to the secondary heating elements 30 and 31 for producing furnace heat. Manually controlled rheostats 41 and 42 may be provided to control the current flow through the secondary heating elements 30 and 31, respectively. It is within the contemplation of the present invention to employ automatic controls in lieu of the manual controls 41 and 42 for fine resistance adjustment and fine current regulation. The opposite ends of the heating elements 30 and 31 may be connected to opposite end terminals of the primary winding and a source of power may be connected to adjacent inner taps of the secondary windings. In this manner, the secondary and primary windings may be connected in series and, yet, electrically insulated from one another. There is present minimum thermal insulation between the primary and secondary windings.

In order to compensate for the exponential rise in the thermal and radiation losses in the entrance zone A and the exit zone C, respectively, the secondary heating elements 30 and 31 are, respectively, non-uniform and non-linear in resistance taken on a turn-by-turn basis and progressing in the axial direction of the helical or spiral windings thereof.

The present invention provides for a varying resistance for the secondary heating elements 30 and 31 on a turn-by-turn basis to compensate for the exponentially rising thermal and radiation losses by creating through the secondary heating elements 30 and 31 a complementary heating curve along the axis of the housing 11 in the entrance zone A and the exit zone C, so that the heat produced by the secondary windings 30 and 31 along the referred to axis substantially equals the referred to thermal and radiant losses along the referred to axis. In this manner, the heating temperature along the axis of the housing 11 within the entrance zone A and the exit zone C is maintained uniform.

Toward this end, the preferred embodiment provides for the securing of heating element material, such as the material from which the secondary heating elements 30

and 31 are made to each turn individually of the secondary heating elements 30 and 31, thereby decreasing the resistance of the turns of the secondary heating elements 30 and 31. The quantity of additional material applied to the respective turns of the heating elements 30 and 31, respectively, will be non-uniform and non-linear and will vary from turn-to-turn. For example, with regard to the entrance zone A, the minimum added quantity of heating element material will be added to the turn contiguous to the entrance opening 12. On the other hand, the maximum added quantity of heating element material will be added to the turn contiguous with or within the center zone B. The quantity of material to be added to each turn of the secondary heating element 30 between the aforementioned minimum and maximum quantities will gradually and successively vary between the aforementioned extremes.

In a similar manner, the minimum quantity of additional material applied to the secondary heating element 31 will be on the turn thereof in exit zone C contiguous to the exit opening of the housing 11. On the other hand, the maximum added quantity of heating element material will be added to the turn contiguous with or within the center zone B. The quantity of material to be added to each turn of the secondary heating element 31 between the aforementioned minimum and maximum quantities will gradually and successively vary between the aforementioned extremes.

It is recognized that the secondary heating elements 30 and 31 can be integrally formed to achieve the intended results without the procedure of adding heating element material. Stated otherwise, initially and at the time of manufacture, the heating elements 30 and 31 can be formed with non-uniform and non-linear resistance varying at a successive and increased rate. Also, it is apparent that an entire turn need not be changed, but a portion thereof could have an added quantity of heating element material to effect the above-described intended results. Lastly, it is within the contemplation of the present invention that distances between turns of windings can be varied to achieve the non-uniform heating to compensate for the exponential thermal and radiant heating losses in the entrance zone A and the exit zone C.

From the foregoing, it is to be observed that the present invention achieves in a cylindrical or tubular furnace substantially a flat thermal response along the axis of the furnace throughout the axial length thereof.

While helically wound heating resistance elements have been referred to, it is apparent that the heating elements may constitute tungsten wire mesh, sheet elements, ceramic heating elements or any other suitable resistance heating elements.

It is to be understood that modifications and variations of the embodiment of the invention disclosed herein may be resorted to without departing from the spirit of the invention and the scope of the appended claims.

Having thus described my invention, what I claim as new and desire to protect by Letters Patent is:

1. A heating assembly for an electric furnace comprising a housing, a tubular wall in said housing constituting a heating chamber, a non-linear resistance in said housing for heating said chamber and for rendering the heat uniform in said chamber along the axis of the entire length of said tubular wall, and means for conducting electric energy to said resistance.

2. A heating assembly for an electric furnace comprising a housing, a tubular wall in said housing constituting a heating chamber, an non-uniform resistance in said housing for heating said chamber and for rendering the heat uniform in said chamber along the axis of the entire length of said tubular wall, and means for conducting electric energy to said resistance.

3. A heating assembly for an electric furnace with non-uniform heat loss characteristics comprising a housing, a wall in said housing for forming a heating chamber,

a non-linear resistance in said housing for heating said chamber to compensate for the non-uniform heat losses for rendering the heat in said chamber more uniform, and means for conducting electric energy to said resistance.

4. A heating assembly for an electric furnace with non-uniform heat loss characteristics comprising a housing, a wall in said housing for forming a heating chamber, a non-uniform resistance in said housing for heating said chamber to compensate for the non-uniform heat losses for rendering the heat in said chamber more uniform, and means for conducting electric energy to said resistance.

5. A heating assembly for an electric furnace with non-uniform heat loss characteristics comprising a housing, a wall in said housing for forming a tubular heating chamber, said heat loss characteristics being non-uniform along the axis of said chamber, a non-linear resistance disposed in said housing along an axis coincident with the axis of said chamber to compensate for the non-uniform heat losses along said axis of said chamber for rendering the heat more uniform in said chamber along the axis thereof, and means for conducting electric energy to said resistance.

6. A heating assembly for an electric furnace with non-uniform heat loss characteristics comprising a housing, a wall in said housing for forming a tubular heating chamber, said heat loss characteristics being non-uniform along the axis of said chamber, a non-uniform resistance disposed in said housing along an axis coincident with the axis of said chamber to compensate for the non-uniform heat losses along said axis of said chamber for rendering the heat more uniform in said chamber along the axis thereof, and means for conducting electric energy to said resistance.

7. A heating assembly for an electric furnace with exponential heat loss characteristics comprising a housing, a wall in said housing for forming a tubular heating chamber, said heat loss being exponential along the axis of said chamber, a non-linear resistance disposed in said housing along an axis coincident with the axis of said chamber to compensate for the exponential heat losses along said axis of said chamber for rendering the heat more uniform in said chamber along the axis thereof, and means for conducting electric energy to said resistance.

8. A heating assembly for an electric furnace with exponential heat loss characteristics comprising a housing, a wall in said housing for forming a tubular heating chamber, said heat loss being exponential along the axis

of said chamber, an non-uniform resistance disposed in said housing along an axis coincident with the axis of said chamber to compensate for the exponential heat losses along said axis of said chamber for rendering the heat more uniform in said chamber along the axis thereof, and means for conducting electric energy to said resistance.

9. A heating assembly for an electric furnace with exponential heat loss characteristics comprising a housing, a wall in said housing for forming a tubular heating chamber, said heat loss characteristics being exponential along the axis of said chamber, a heating resistance disposed in said housing along an axis coincident with the axis of said chamber, said heating resistance being formed with its resistance varied as said heating resistance progresses axially to compensate for the exponential heat losses along said axis of said chamber for rendering the heat more uniform in said chamber along the axis thereof, and means for conducting electric energy to said heating resistance.

10. A heating assembly for an electric furnace with exponential heat loss characteristics comprising a housing, a wall in said housing for forming a tubular heating chamber, said heat loss characteristic being exponential along the axis of said chamber, a primary uniform heating resistance disposed in said housing along an axis coincident with the axis of said chamber for heating said chamber, a secondary heating resistance disposed in said housing along an axis coincident with the axis of said chamber, said secondary heating resistance being formed with its resistance varied as said secondary heating resistance progresses axially to compensate for the exponential heat losses along said axis of said chamber for rendering the heat in said chamber more uniform along the axis thereof, and means for conducting electric energy to said heating resistance.
